UNITED STATES PATENT OFFICE.

JOSEPH FREUND, OF WAMPUM, PENNSYLVANIA.

RAIL-BED FOR RAILROADS.

SPECIFICATION forming part of Letters Patent No. 715,049, dated December 2, 1902.

Application filed August 18, 1902. Serial No. 120,155. (No model.)

To all whom it may concern:

Be it known that I, JOSEPH FREUND, a citizen of the United States of America, residing at Wampum, in the county of Lawrence and 5 State of Pennsylvania, have invented new and useful Improvements in Rail-Beds for Railroads, of which the following is a specification.

This invention relates to rail-beds for railroads; and it consists in certain improvements in the construction thereof, as will be hereinafter fully described, and pointed out in the claims.

The invention is illustrated in the accompanying drawings, as follows:

15 Figure 1 shows a plan view of a railroad having rail-beds arranged according to my invention. Fig. 2 shows a section on the line 2 2 in Fig. 1.

A marks the rail, which is of the ordinary 20 form; B, the rail-beds. The rail-beds have formed in them the tenons b^1 and mortises b^2 , the two being adapted to form an interlocking means between the beds for maintaining a fixed lateral relation between them, or, in 25 other words, for preventing the spreading of the rails. The beds are also provided with tenons b^3 and mortises b^4 , these forming an interlocking means for maintaining a fixed longitudinal relation between the beds.

30 The beds are diamond-shaped in general contour. This gives a large surface and still permits of the introduction of implements for the adjustment of ballast, &c. This shape also brings the interlocking means into proper 35 relation with the greatest strength of the intermediate material.

The beds are provided with the grooves b^4 . These extend diagonally across the beds. The outside of the groove is fastened to fit 40 the outer surface of the rail. The groove is of sufficient width to permit of the rail being introduced directly from the top of the groove, and wedge C is arranged between the opposite side of the groove and the opposite side 45 of the rail and forces the rail against the surface b^5 , holding it in proper position. The groove is provided with a series of enlargements b^6 , by means of which the wedges C may be introduced. The groove is provided 50 with the undercut b^7 , and the wedge is formed to fit in this undercut portion, thus locking the wedge against displacement upwardly.

This arrangement of the wedge locks the rail against the bottom of the groove.

I prefer to form these beds of cement and 55 to place the fish-plates D, with the bolts d, in the side of the groove and secure them in place as the bed is formed.

What I claim as new is—

1. As articles of manufacture, rail-beds for 60 railroads one for each rail, having formed integrally therewith interlocking means for maintaining a fixed lateral relation between the beds.

2. As articles of manufacture, a series of 65 rail-beds for supporting a rail having formed integrally therewith interlocking means for maintaining a fixed longitudinal relation between the beds.

3. As articles of manufacture, rail-beds for 70 railroads one for each rail having formed integrally thereon a mortise-and-tenon interlocking means for maintaining a fixed lateral relation between the beds.

4. As articles of manufacture, a series of 75 rail-beds for supporting a rail, having formed immediately thereon mortise-and-tenon interlocking means for maintaining a fixed longitudinal relation between the beds.

5. As an article of manufacture, a rail-bed, 80 diamond-shaped in general contour and having a groove therein arranged diagonally to the bed.

6. As articles of manufacture, rail-beds for railroads, diamond-shaped in general contour; 85 said beds being arranged to place the rail diagonally thereon and having formed immediately thereon interlocking means for maintaining a fixed lateral relation between the beds. 90

7. As articles of manufacture, a series of rail-beds, diamond-shaped in general contour and arranged to have the rail placed diagonally thereon, and having formed immediately 95 thereon interlocking means for maintaining a fixed longitudinal relation between the beds.

8. As articles of manufacture, a series of rail-beds for railroads, one series for each rail having formed integrally therewith interlocking means for maintaining a fixed lateral and 100 longitudinal relation between the beds.

9. As articles of manufacture, a series of rail-beds for railroads one series for each rail, having formed immediately thereon mortise-

and-tenon interlocking means for maintaining a fixed lateral and longitudinal relation between the beds.

10. As articles of manufacture, a series of 5 rail-beds for railroads one series for each rail; said beds being diamond-shaped in general contour and arranged to have the rails placed diagonally thereon; said beds having formed thereon interlocking means for maintaining 10 a fixed lateral and longitudinal relation between the beds.

11. As an article of manufacture, a rail-bed having a groove therein against which one side of the rail abuts in combination with the 15 wedge arranged between the opposite wall and the opposite side of the rail.

12. As an article of manufacture a rail-bed having a groove therein against which one side of the rail abuts in combination with the 20 wedge arranged between the opposite wall and the opposite side of the rail; said groove being provided with enlargements for the introduction of the wedge.

13. As an article of manufacture a rail-bed 25 having a groove against the side of which one side of the rail abuts the opposite side of the groove being undercut in combination with the wedge, arranged between said opposite

wall and the opposite side of the rail, the wedge being formed to fit the undercut for 30 the purpose described.

14. As an article of manufacture a rail-bed formed of cement having a groove therein for the reception of the rail in combination with a fish-plate secured in the bed at the side of 35 the groove in the formation of the bed.

15. As an article of manufacture, a series of rail-beds of cement, one series for each rail and each bed being provided with a mortise-and-tenon construction for uniting them laterally and longitudinally and each being provided with a groove b^4 , one side b^5 being shaped to conform with the rail, the opposite side b being provided with an undercut b^7 and the enlargements b^6 ; in combination with 40 the wedge C arranged to fit the undercut b^7 ; and the fish-plate D secured in the side of the groove in the formation of a bed.

In testimony whereof I have hereunto set my hand in the presence of two subscribing 45 witnesses.

JOSEPH FREUND.
